UNITED STATES PATENT OFFICE.

GUSTAV GOLDMAN, OF BALTIMORE, MARYLAND.

KNIFE WITH SEPARABLE BLADE.

Application filed January 17, 1925. Serial No. 3,159.

To all whom it may concern:

Be it known that I, GUSTAV GOLDMAN, a citizen of the United States of America, and a resident of Baltimore, Maryland, have invented new and useful Improvements in Knives with Separable Blades, which invention is fully set forth in the following specification.

This invention relates to knives with removable, separable or interchangeable blades designed for surgical or other uses, and is an improvement on the structure shown, described and claimed in U. S. Patent 1,506,897, dated Sept. 2, 1924. The interchangeable blades in knives of this character are of very thin sheets of metal and as they are designed for uses such as surgical operations and the like, it is essential that the blades should be firmly held in position and absolutely restrained from any lateral or longitudinal play in the handle portion of the knife.

In the patent mentioned above the handle portion of the knife is composed of two longitudinal portions secured together by a mortise and tenon construction, with the blade held between the two longitudinal parts of the handle and one of these longitudinal portions is provided with an overhanging lateral flange extending at a right angle over the top of the other portion and serving as a finger rest in the use of the knife and an abutment against which the top of the blade reacts when cutting pressure is applied to the knife. It has been found in practice that this leaves the blade free to have lateral play, particularly if the handle portion of the blade is moved to one side or the other in the cutting action. One object of the present invention is to eliminate this lateral play to the blade. When the blade is in position between the two handle portions it is absolutely essential that the blade be held with great firmness while at the same time providing a construction in which the movement of the parts to assemble and disassemble the blade from the handle portion may be readily accomplished, and a further object of the invention is to assure such firm retention of the blade in position on the handle portion and at the same time provide handle portions which may be manipulated with facility to assemble and disassemble the blade, but which may be retained in assembled position with such firmness that they cannot be

readily or accidentally misplaced so as to loosen the blade. With these objects in view the invention consists of the construction and combination of elements herein-after described, and then more specifically pointed out in the claims.

In the accompanying drawings, showing one form which the inventive idea may assume—

Fig. 1 is a side elevation of a knife embodying the invention;

Fig. 2 is a top plan view thereof;

Fig. 3 is a side elevation of one of the handle portions showing the means of assembling the blade with relation thereto;

Fig. 4 is a vertical transverse section on the line 4—4 of Fig. 1;

Fig. 5 is a section in plan on the line 5—5 of Fig. 1.

In said drawings, in which like reference numerals indicate like parts throughout the several views, 1 is the blade which is in the form of thin sheet metal having its rear end 2 preferably inclined downwardly and rearwardly from the top edge of the blade. This blade has a slot 3 which throughout the greater portion of its length has approximately parallel sides, but which at its forward end 6 has an enlarged opening. The handle of the knife, as in the patent aforementioned, is composed of two longitudinal halves or members 7 and 8. The handle member 7 is slightly cut away or recessed at its forward end portion 9, to a depth equal to the thickness of the blade 1, said cut-away portion having an upwardly and forwardly inclined shoulder 10, and projecting laterally from said cut-away portion is a headed pin 11. The upper edge of the forward portion of the handle member 7, and extending approximately throughout the length of the cut-away or recessed portion 9, is provided with an outwardly and downwardly extending bevel 12 (see Fig. 4) and when the blade 1 is in position the top of the blade preferably extends very slightly above the inner edge of this bevel 12, as indicated at 1^a in Fig. 4. The rearward portion of the handle member 7 is provided with a laterally extending pin 13 having an oblong rectangular-shaped head 13^a with its longer dimension extending transversely of the handle member 7.

The handle member 8, forming the other longitudinal half of the handle, is provided with an oblong slot 14, the rear end of which

slot is approximately opposite the pin 13 on the handle member 7, when the parts are in assembled position, and in which position the oblong head 13^a of the pin 13 extends transversely of the slot 14 as clearly shown in Fig. 1.

The outer surface of the handle member 8, adjacent the pin 13, is slightly inclined, as clearly shown at 8^a in Fig. 5, the handle member being thicker at the rear end of the slot 14 than at the forward end, and the thickness of said member at the rear end being such that it slides under the head 13^a with close frictional engagement.

15 The forward portion of the handle member 8 is provided with a laterally and downwardly extending flange 15, which flange, on its under side immediately opposite the blade 1, may be slightly grooved to receive 20 the upper edge portion of the blade, and that portion of the flange which overlies the handle member 7, and immediately opposite the bevel 12 thereon, is beveled from said groove outwardly and downwardly as 25 shown at 16, Fig. 4, so that when said parts are assembled the bevel 12 is snugly engaged by the bevel portion 16. The forward end of the handle member 8 is provided with a forwardly opening slot 17 having a downwardly and outwardly inclined cam surface 30 portion 17^a on its forward lower edge. This slot is so proportioned that when the parts are in the assembled position shown in Fig. 1, it engages the pin 11 with the head of the 35 pin fitting snugly against the outer surface of the handle member 8 as will be clearly understood from an inspection of Fig. 4.

To assemble the parts the handle portion 40 8 is moved rearward until the slot 17 disengages from the pin 11, when the handle portion 8 may be turned upon the pin 13 as shown in dotted lines in Fig. 1. The enlarged opening 6 of the slot 3 of the blade is then passed over the head of the pin 11 45 and the blade turned until the inclined rear end portion 2 thereof meets the forwardly inclined abutment 10 on the handle member 7. The handle member 8 is then turned downwardly, turning around the pin 13 50 until the flange 15 is brought down upon the top of the blade and the top of the beveled portion 12 of the handle member 7, and the handle member 8 is then moved forward until the rear end of the slot 17 engages the pin 11. The head of the pin, being 55 slightly larger than the width of the slot, engages with the outer surface of the handle member 8. By reason of the engagement of the cam 17^a with the pin 11, the flange 15 60 is drawn forcibly and firmly downward into engagement with the blade 1 and by the engagement of the beveled portion 16 on said handle member 8 with the beveled face 12 on the handle member 7 the two members are drawn into firm engagement with

both sides of the blade and retained so that any movement of the blade to either side, or upward or downward, is absolutely prevented. Furthermore, by reason of the engagement of the inclined face portion 8^a 70 along the slot 14 with the under side of the head 13^a of the pin 13, the two members 7 and 8 are brought into intimate contact along their inner faces and are held in such relation by the frictional engagement of said wedge-like surface 8^a with the under side of the head 13^a of the pin 13. Nevertheless, the parts may be readily disassembled by firmly gripping the two handle members 7 and 8 with the thumb and fingers along the 80 roughened portions 18, and sliding one of said members longitudinally with reference to the other.

It will be readily understood that, if it is desired to completely separate the two 85 handle members 7 and 8, this may be accomplished by sliding the handle member 8 rearward to the position shown by dotted lines in Fig. 1 and then turning it at right angles to the member 7 so that the head 13^a 90 of the pin 13 will pass out of the slot 14.

From the foregoing it will be seen that the invention provides a knife with a separable blade which may be readily and quickly 95 separated or removed therefrom, but which, nevertheless, when in position is absolutely restrained from movement either longitudinally, laterally or up and down, and at the same time is provided with an efficient finger rest for the forefinger when using the 100 knife as it would be used in many surgical operations.

The specific description of the invention herein given is that of one embodiment of the inventive idea, but it will be readily recognized by those skilled in the art that the invention may assume other specific forms without departing from the limits of the invention as such limits are defined in the 105 appended claims.

What is claimed is:—

1. In a knife with separable blade, a handle divided into two longitudinally extending parallel halves or portions, a blade between said portions, and two cam engagements between said portions adjacent said blade one of which imparts vertical and the other lateral clamping action to said portions.

2. In a knife with separable blade, a handle divided into two longitudinally extending parallel halves or portions one of which has a flange extending laterally over the upper edge of the other, a blade between the forward ends of said handle portions, a pin on the one portion passing through an opening in the blade and engaged by a vertically acting cam on the flanged portion.

3. In a knife with separable blade, a handle divided into two longitudinally extend-

ing parallel halves or portions one of which portions has a lateral flange with a cam surface engaging the upper edge of the other portion, a blade between said portions, and means forcing said cam into engagement with said edge by relative longitudinal movement of said handle portions.

4. In a knife with separable blade, a han-

- 10 dle divided into two longitudinally extending parallel halves or portions, one of which has a laterally extending flange longitudinally grooved on its under surface, a blade between said portions with its upper edge in the groove of said flange, and means forcing 15 the upper edge of the blade into the said groove by relative longitudinal movement of said handle portions.

5. In a knife with separable blade, a han-

- 20 dle divided into two longitudinally extending parallel halves or portions one of which is beveled on its upper forward edge and the other of which is provided with a lateral downwardly extending flange beveled on its under surface, a blade between said portions, and a cam-acting pin and slot connection be- 25 tween said handle portions forcing said beveled surfaces into cooperative relation to clamp said blade.

6. In a knife with separable blade, a han-

- 30 dle divided into two longitudinally extending parallel halves or portions, pin and slot connections between said portions, a blade clamped between said portions at their for- 35 ward ends, a flange on one portion overhang- ing said blade and the upper edge of the

other portion, and cooperating cam surfaces on said upper edge and on said flange to force said handle portions into close clamping engagement with the blade.

7. In a knife with separable blade, a han- 40 dle divided into two longitudinally extending parallel halves or portions, pin and slot connections between said portions whereby they may have relative longitudinal movement, a blade clamped between the forward 45 ends of said handle portions, a flange on the forward end of one of said portions overhanging the upper edge of the forward end of the other portion, and cooperating cam surfaces on said portions to force them into 50 clamping engagement.

8. In a knife with separable blade, a han- 55 dle divided into two longitudinally extending parallel halves or portions, a blade be- 60 tween the forward ends of said portions, a headed pin on one portion and passing through an opening in said blade and through a slot in the other portion the outer surface of which passes under and engages the head of said pin, a cam surface on the lower edge of said slot engaging said pin, and a second headed pin near the rear end of one of the handle portions and passing through a slot in the other portion the under side of the head of said pin engaging an inclined wedge-like surface on the outer face of said last-named handle portion.

In testimony whereof I have signed this specification.

GUSTAV GOLDMAN.
